UNITED STATES PATENT OFFICE.

WILLIAM H. DALTON, OF WEST HOBOKEN, NEW JERSEY.

DESIGN FOR A PENCIL-DISPLAY STAND.

41,538.

Specification for Design.

Patented July 4, 1911.

Application filed April 21, 1911. Serial No. 622,637. Term of patent 7 years.

To all whom it may concern:

Be it known that I, WILLIAM H. DALTON, a citizen of the United States, residing in West Hoboken, in the county of Hudson and State of New Jersey, have invented a new, original, and ornamental Design for a Pencil-Display Stand, of which the following is a specification, reference being had to the accompanying drawing, forming a part thereof.

The figure is a perspective view of a pencil display stand, illustrating my new design.

I claim:

The ornamental design for a pencil display stand, as shown.

WILLIAM H. DALTON.

Witnesses:

SOPHIA FRANCOIS,
WILLIAM HENDERSON.
